UNITED STATES PATENT OFFICE.

CHARLES EDWARD HAVILAND, OF LIMOGES, FRANCE.

DESIGN FOR A COVER-DISH.

SPECIFICATION forming part of Design No. 22,622, dated July 18, 1893.

Application filed June 22, 1893. Serial No. 478,515. Term of patent 14 years.

To all whom it may concern:

Be it known that I, CHARLES EDWARD HAVILAND, a citizen of the United States, residing at the city of Limoges, in the Republic of France, have invented and produced a new and original Design for a Cover-Dish and other Articles, of which the following is a specification, reference being had to the accompanying drawings, forming part thereof, and in 10 which—

Figure 1 is a side elevation of a dish bearing my design. Fig. 2 is a top view of same, the outline of the upper edge of the body of the dish being shown through the cover by dotted lines, and Fig. 3 is a vertical section through one side of the dish on the dotted line 3—3 of Fig. 2.

15 The leading feature of my design consists of the ornamental form and configuration of the dish, as hereinafter referred to and shown in the drawings. The rim inclosing the body of the dish is formed of two sections A, B, the former being slightly concave along its upper portion and thence extending downward and outward to the line C, where it meets 25 the lower section B which curves downward and inward to the ornamental base D, as shown in Figs. 1 and 3. The rim of the body of the dish has at definite intervals the depressions or grooves E which disappear down 30 the lower section B and sub-divide the rim into the scalloped sections F, G. The cover of the dish has along its edges the scalloped sections H, I, conforming with the outline of the rim of the body of the dish, and at the central 35 field of the cover is the raised portion J bearing the handle K. At opposite ends of the dish are handles L.

What I claim is—

The design for a cover-dish, substantially 40 as shown and described.

Signed at the city of New York, in the county and State of New York, this 20th day of June, 1893.

CHARLES EDWARD HAVILAND.
